(57) **CLAIM**

The ornamental design for a construction toy component, as shown and described.

DESCRIPTION

FIG. 1 is a top perspective view of a construction toy component;

FIG. 2 is a top plan view of the construction toy component of FIG. 1;

FIG. 3 is a side elevation view of the construction toy component of FIG. 1, the other side being identical; and,
FIG. 4 is an end elevation view of the construction toy component of FIG. 1, the other end being identical.

The bottom forms no part of the claimed design.
